UNITED STATES PATENT OFFICE.

WILLIAM H. BRISTOL, OF WATERBURY, CONNECTICUT.

SYNCHRONIZED MOTION-PICTURE APPARATUS.

Application filed December 31, 1920. Serial No. 434,240.

To all whom it may concern:

Be it known that I, WILLIAM H. BRISTOL, a citizen of the United States, and a resident of Waterbury, in the county of New Haven and State of Connecticut, have invented certain new and useful improvements in Synchronized Motion-Picture Apparatus, of which the following is a specification.

The invention relates to synchronized motion picture apparatus such as may be employed in combination with a phonograph or other entertainment apparatus, for example as set forth in my prior U. S. Patent No. 1,234,127, dated July 24th, 1917.

The invention has for its object, more particularly, to provide a projection unit which may be driven in the usual manner for non-synchronized operation and readily converted for synchronizing the projector with other apparatus and also arranged for conveniently resynchronizing the same in the event of a disturbance of synchronization between the cooperating entertainment apparatus. More especially, the invention relates to means for engaging or disengaging in a simple and convenient manner synchronized driving mechanism from the projecting machine; said synchronized driving mechanism, moreover, being arranged to be influenced for resynchronization purposes by means located conveniently to the operator of the said projector. The entire arrangement is such, moreover, that it will not interfere with the operation of the projection machine in the usual and well-known manner, when it is desired to operate same independently of other apparatus.

In the accompanying drawings which illustrate the invention—

Fig. 1 is a perspective view of the improved projector unit and of a talking machine which may be operated synchronously therewith.

Fig. 2 is a detail elevation of the motion picture projector head and mechanism connecting the synchronized motor mechanism thereto.

Similar characters of reference designate corresponding parts throughout the several views.

Referring to the drawings, 10 designates a motion picture apparatus of standard and well-known construction and which may be carried by a suitable supporting stand or the like 11. The apparatus includes a driv-

ing shaft 12 and transmission mechanism 13, whereby the rotation of the film advancing and shutter operating mechanism is effected, all of which is well understood and form no particular part of the present invention.

The said driving shaft 12 is designed to be rotated by means for non-synchronized driving of same, for example, it may receive a handle 14 for manual operation of the mechanism; or, the said shaft may be operated from an electric motor 15 carried by the stand 11 as through a belt 16 fitting a pulley 17 of the transmission mechanism.

When it is desired to operate the mechanism synchronously with other apparatus, the motor drive aforesaid may be readily disengaged as by removing the belt 16 from the pulley 17. A synchronized driving member as the motor mechanism 20, arranged for example as set forth in my co-pending application Serial No. 313,263, is mounted on a suitable base 21 situated if desired within the stand 11, and is designed to rotate a vertically disposed drive shaft 22 synchronously with the rotation of other entertainment mechanism, as the talking machine apparatus 23. The drive shaft 22 is of a flexible nature to allow for conveniently adapting same to and alining it with the projecting machine drive mechanism.

To this end, universal joints 24, as well as a sliding connection 25 intermediate same, are provided in the shaft; and its upper end terminates in a bevel pinion 26. The shaft may be conveniently mounted at its upper end in a bearing 27 of a bracket member 28 secured to and carried by, for example, the stereopticon rod 29 of the projector. On the driving shaft 12 of the projector is mounted a bevel gear wheel 30 arranged to slide along said shaft and to be held thereto, as by a spring catch 30', in position to mesh with the bevel pinion 26, Fig. 2, and thereby to transmit the rotation of the shaft 22 and effect the advance of the film and operation of the shutter mechanism of the projector, similarly to the operation by the non-synchronized motor apparatus 15, or hand crank 14. When it is desired to operate the projecting machine synchronously with other apparatus, the belt 16 and handle 14 are detached and the gear wheels 26 and 30 brought into mesh, as aforesaid.

In addition, the rotation of the shaft 22 is arranged to be varied for resynchronizing purposes through the operation of an associated device by rotating the stator member 31, of the motor mechanism 20, more particularly as set forth in U. S. Letters Patent No. 1,228,678, dated June 5th, 1917. This may be conveniently effected through the operation of a connecting flexible shaft 32 attached to a hand wheel 33. The latter may be secured to the stand conveniently to the operator of the machine and serves thereby to rotate the stator member 31 of the motor apparatus in either direction accordingly as it may be desired to advance or retard the film of the projecting machine.

In this manner, a very convenient arrangement is afforded whereby the synchronizing apparatus may be readily connected to and associated with a projecting machine, and the latter driven either non-synchronously or synchronously with some other apparatus, while the resynchronizing mechanism associated therewith affords a ready means for taking care of any defects in the film or unforeseen contingencies.

I claim:—

1. In synchronized entertainment apparatus, including a motion picture machine, two driving means associated with said machine, one of which is synchronized with a device of the entertainment apparatus, means to connect same with the motion picture machine and including a flexible driving connection, and means to engage said connection with and disengage same from said motion picture machine.
2. In synchronized entertainment apparatus, including a motion picture machine: two driving means associated with said machine, one of which is synchronized with a device of the entertainment apparatus, a bearing bracket secured to the motion picture machine, a vertically disposed drive shaft mounted for rotation therein and

driven from the synchronized driving means, said shaft terminating at the motion picture machine end in a bevel pinion, and a slideable bevel gear wheel connected with the motion picture machine transmission mechanism and adapted to mesh with said pinion.

3. In synchronized entertainment apparatus, including a motion picture machine: two driving means associated with said machine, one of which is synchronized with a device of the entertainment apparatus, a bearing bracket member mounted on the stereopticon rod of the motion picture machine, a vertically disposed drive shaft mounted for rotation therein and driven from the synchronized driving means, said shaft terminating at the motion picture machine end in a bevel pinion, and a slideable bevel gear wheel connected with the motion picture machine transmission mechanism and adapted to mesh with said pinion.

4. In synchronized entertainment apparatus, including a motion picture machine, two driving means associated with said machine, one of which is synchronized with a device of the entertainment apparatus, means to connect same with the motion picture machine and including a drive shaft provided with a universal joint, and means to engage said shaft with and disengage same from the said motion picture machine.

5. In synchronized entertainment apparatus, including a motion picture machine, two driving means associated with said machine, one of which is synchronized with a device of the entertainment apparatus, means to connect same with the motion picture machine and including a drive shaft provided with a universal joint and with a sliding connection, and means to engage said shaft with and disengage same from the said motion picture machine.

Signed at New York, in the county of New York and State of New York, this 28th day of December, A. D. 1920.

WILLIAM H. BRISTOL.
